(57) **CLAIM**

The ornamental design for a game call, as shown.

DESCRIPTION

FIG. 1 represents a side elevational view of a first embodiment of the game call of the present invention;

FIG. 2 represents a perspective view of the game call of the present invention;

FIG. 3 represents a side elevational view of a second embodiment of the game call of the present invention; and,
FIG. 4 represents a perspective view of the game call of the present invention.

The broken line showing of display characters is included for the purpose of illustrating unclaimed subject matter and forms no part of the claimed design.

1 Claim, 4 Drawing Sheets

FIG. 3
